UNITED STATES PATENT OFFICE.

JAMES B. PULLMAN, OF LOS ANGELES, CALIFORNIA.

IMPROVEMENT IN SUBSOIL-PLOW.

Specification forming part of Letters Patent No. **89,432**, dated April 27, 1869.

To all whom it may concern:

Be it known that I, JAMES B. PULLMAN, of Los Angeles, in the county of Los Angeles and State of California, have invented a new and useful Improvement in Subsoil-Plows; and I do hereby declare that the following is a full, clear, and exact description thereof, which will enable others skilled in the art to make and use the same, reference being had to the accompanying drawings, forming part of this specification, in which—

Figure 1 is a side view of the stock and colter and a sectional view of the share. Fig. 2 is a front view of the colter and share from a section through the beam in front of the colter.

Similar letters of reference indicate corresponding parts.

The object of this invention is to provide a subsoil of light draft and effective action.

It consists in the combination of a share of peculiar construction with a colter having a concave cutting-edge, both being affixed to a plow-stock of the usual construction.

In the drawings, A B C is the plow-stock, to which my improvements are attached. The colter D has a concave cutting-edge, and its upper end is formed with a bolt-shank, which passes through the beam, and is secured by a nut, d. The lower end of the colter is affixed to the share a short distance in rear of the point f of the latter. The share is curved

vertically, as shown, and is formed with a V-shaped cross-section, as indicated in Fig. 1.

It is further formed with a triangular flat base, g f g, from which the rear and concave edges h h spring. The share is again widened at i i, from which points the edges j j taper. This formation of the share delivers the subsoil off laterally, working some of it to the top of the furrow. The share is bolted to the stock by the bolts a and e and to the colter by the bolt b.

G is a heel-plate or brace-plate, which is affixed to the part B and the share by the respective bolts a and b. This plate serves to strengthen the attachment of the share, and to increase longitudinally the base-surface of the share, thereby conduced to its more steady movement.

The share and colter are usually of steel and the heel-plate of iron. The share and colter are readily taken apart to sharpen them.

Having thus described my invention, I claim as new and desire to secure by Letters Patent—

The combination, in a subsoil-plow, of the share E, colter D, and heel-plate G with the stock A B C, substantially as and for the purpose herein shown and described.

JAMES B. PULLMAN.
